Ernest Herrmann, Great Neck, N. Y., assignor to Home Furniture Co., York, Pa., a corporation of Pennsylvania

Application October 24, 1949, Serial No. 5,672

Term of patent 3½ years

(Cl. D33—6)

To all whom it may concern:

Be it known that I, Ernest Herrmann, a citizen of the United States, residing at Great Neck, Long Island, New York, have invented a new, original, and ornamental Design for a Chest of Drawers, of which the following is a specification, reference being had to the accompanying drawing, forming a part thereof.

In this showing:

Fig. 1 is a perspective view of the chest of drawers,

Fig. 2 is a front elevation, while

Fig. 3 is a side view.

The dotted line showing of handles and base in the figures of the drawing are for purposes of illustration only.

I claim:

The ornamental design for a chest of drawers, as shown and described.

ERNEST HERRMANN.
